UNITED STATES PATENT OFFICE

FREDERICK W. LINAKER, OF BROOKLYN, NEW YORK

BOILER CLEANER

Application filed July 3, 1929. Serial No. 375,772.

This invention relates to improvements in cleaners for water tube boilers, super-heaters, or the like, and aims to provide certain improvements therein.

In this type of apparatus there extend into the boiler between the tubes a series of cleaner units which comprise rotatable steam pipes provided with a series of jet openings which when steam is admitted to them blow the ashes, etc. from the tubes. Such units are usually connected at the exterior of the boiler wall with an operating head containing a steam chamber which is connected to the boiler, and a valve which is designed to control the passage of steam from said chamber to the cleaner unit. Means are customarily provided for rotating the cleaner unit and for opening and closing the valve.

The present invention is particularly directed to a construction in which there is a common means for opening the valve and rotating the unit, and in its preferred form operates first to open the valve and then turn the unit through a predetermined arc, whereupon the unit may be returned to its initial position and the valve then closed. Among the objects of the present invention is to provide a cleaner of this type which is of cheap and simple construction and in which there is a positive sequence of operations, and a certainty of properly closing and unclosing the valve. The invention has certain other advantages which will be more fully described.

Referring to the drawings which illustrate one form of the invention:

Figure 1 is a central, vertical section of the outer end of a boiler cleaner embodying the preferred form of the invention.

Fig. 2 is a horizontal section taken on the line 2—2 in Figure 1, Fig. 2a being a continuation of Fig. 2.

Fig. 3 is a vertical section taken on the line 3—3 of Figure 1.

Fig. 4 is a cross-sectional view.

Fig. 5 is a central, vertical section of a modified form.

Fig. 6 is a section on the line 6—6 in Fig. 5.

Referring first to Figs. 1 to 4 of the drawings let A indicate the outer end of a cleaner element shown as a tube extending through a

section of boiler wall B and designed to project into the interior of the boiler. C is a continuation of the cleaner A and is connected with it by means of flanges D and E, the flange D being screwed and keyed to the section A, and the flange E being similarly connected to the section C, and the two parts being screwed together by screw bolts F. G is the operating head having at its upper part a gland or stuffing box H into which the section C of the cleaner extends, and within which the latter may rotate. The head G has a stem inlet H' leading to a steam chamber I which is connected to a steam passage J through a valved opening K, the passage J leading to the end of the extension C of the cleaner and being adapted to convey steam thereto when the steam valve L opens the passage through the opening K. A valve seat M is best provided which is screwed into the head as shown.

The valve L is carried on a valve spindle N which projects through a gland or stuffing box O carried by a bracket P which is secured to the head G in any suitable manner.

To operate the valve L I provide a gear Q which is splined to the spindle N in such manner as to turn the latter, and also to permit the spindle to slide with relation to the gear, the latter being confined against lateral movement in the bracket P as shown in Figure 1. By reference to Fig. 2 it will be seen that the gear Q is turned by a similar gear R carried on a shaft S, the extension of which is shown in Fig. 2a, the shaft S being turned by a sheave wheel, or other operating mechanism, T, a portion of which is shown in this figure.

Upon turning the sheave T the spindle N is, hence, rotated and is caused to travel to the left in Figure 1 to open the valve L by means of screw threads U which turn in a fixed nut V.

The spindle N is also adapted to turn a small gear W which is formed on, or connected to, a rotating piece X which has a bearing in a cylindrical portion Z, and which is of itself prevented from moving longitudinally by a set screw A' working in an annular groove B' in the rotating piece X. The screw-threaded end of the spindle is main-

tained in continuous rotative relation to the piece X while it advances and retracts by a spline C' working in a groove D' in the spindle, as best seen in Figs. 1 and 2.

5 The small gear W serves as a driving means for turning the cleaner A. This is accomplished by a large gear E' which instead of being mounted directly and fixedly upon the cleaner A is mounted on the flange D previously described which is fixed to the cleaner A. The gear E' is so constructed that it has a limited rotative motion upon the flange D, which motion is idle and takes place while the valve is being opened. When this motion 15 is completed, however, a lug X' carried by the gear E' encounters an abutment X² on the flange D, after which the flange and element A are rotated in the direction of the arrows in Figs. 3 and 4.

20 The device operates as follows:

When the parts are in the position of Figure 3 upon the sheave wheel T being operated to the left the valve immediately commences to open, but as the lug X' on the gear E' is 25 against the abutment X² the movement of the gear E' is idle so far as turning the cleaner element is concerned. After several turns of the valve spindle N the valve reaches a position where it is fully open and able to 30 supply the full head of steam to the cleaner. The lug X' on the gear E' then engages an abutment X³ on the flange D and the cleaner is then rotated. A continuance of the rotation of the sheave T in the same direction, 35 hence, rotates the cleaner as far as may be desired, usually for about one-half of a complete revolution. During this time of rotation of the cleaner the valve L is moving further from its seat, and this movement is 40 idle since the valve has already been opened to the extent required before the cleaner is started in its rotation.

When the cleaner is rotated to the desired point the rotation of the sheave T is reversed. 45 This first causes the gear E' to move idly about the cleaner until the lug X' contacts with the abutment X² whereupon the cleaner begins to move in a reverse direction towards its initial position. During this time the 50 valve is also moving idly toward its seat, which movement it continues while the cleaner is being reversely rotated towards its initial position, and preferably the construction is such that the cleaner arrives at such 55 position at the same time that the valve closes.

In Figs. 5 and 6 wherein I have illustrated a slightly modified form of valve motion the arrangement is such that the valve A² closes to the left instead of the right, and is given 60 its opening and closing movements without rotation. To effect this the valve spindle B² is threaded as before, but is provided with an elongated slot C² in which rides a spline D² so that the spindle may have a longitudinal 65 movement but is prevented from any substan-

tial rotary movement. The spindle is moved in and out by a nut E² which is fixed to or formed as a part of a gear F² which meshes with a gear F³ carried on a shaft G² upon which is mounted the sheave wheel H². In Fig. 5 the extension of the shaft is shown in dotted lines. The shaft G² carries also a small pinion I² which meshes with a large gear J² which is mounted to rotate upon a collar K² formed as a part of the flange L² 70 by means of which the cleaner M² is fixed to its extension N². The cleaner M² is provided with a flange O² which is bolted to the flange L². In the construction shown the large gear J² is recessed on its face to receive the flange L² and carries abutments P², Q² which are 75 designed to contact with a lug R² carried by the flange L².

The operation is substantially that heretofore described with regard to Figure 1. 85

When the sheave wheel H² is rotated in an anti-clockwise direction in Fig. 6 the gear F² being in mesh with the gear F³ the valve starts to open. Since the small pinion I² is 90 also in mesh with the gear J² the latter also starts to rotate. This rotation of the gear is idle so far as rotating the cleaner is concerned until the abutment Q² engages the lug R², after which the cleaner starts to move in a clockwise direction from the position shown in Fig. 6, which illustrates the position of the parts at the end of the idle movement of the gear J². Previous to such movement the valve is opened by the rotation of the nut E² to an extent sufficient to admit the full head of steam, and upon the rotation of the cleaner the valve moves idly to a more fully open position until the end of the initial movement of the cleaner. Upon the motion of the sheave wheel being reversed the cleaner stands momentarily stationary until the shoulder P² reaches the lug R² whereupon the cleaner is 100 given a reverse movement to its initial position, the valve during the first part of the reverse operation moving idly toward its seat, and during the last part acting to close the steam opening. Fig. 6 shows a section looking toward the right in Fig. 5, or away from the boiler. Viewed from a point looking to the left in Fig. 5 the initial movement of the sheave wheel is clockwise, and the initial movement of the cleaner is anti-clockwise. These movements, however, may be varied as desired. 105

In prior cleaners having the capacity of opening the valve prior to the turning of the cleaner, it has been found necessary to provide more or less complicated locking means for holding the valve open, or engaging and disengaging means between the drive member and the cleaner tube, or catches of one sort or another for accomplishing these results. The present invention accomplishes the result without resort to any such means, and this is done through a lost motion connection located 110 115 120 125 130

between the operating member, such as the sheave wheel, and the cleaner tube. By a lost motion connection I mean a device which is not disengaged in operation in the sense that it is retracted out of the path of some other part or forcibly locked against movement. I mean that class of devices, one of which is illustrated in the drawings, wherein there is a certainty of connection between the parts after a given amount of idle movement. The amplitude of this idle movement may be adjusted, but there is in any case a certainty of engagement. In such lost motion connections there are usually two movable parts capable of an idle relative movement but constrained to move together in either direction when said idle movement has taken place. In the construction shown the two abutments connected with the cleaner (or with the gear) move in a fixed circular path and engage with a single abutment also moving in a fixed circular path upon the opposite part.

By the use of this connection it will be observed that I eliminate all catches, locks, cams, pawls, throw-off devices, and separately moving parts which are likely to get out of order or break, and produce an extremely simple construction which will perform substantially the same duty. I do not wish to exclude the use of movable engaging parts where the movement is introduced for some other purpose than first giving an opening movement to the valve and then a turning movement to the cleaner and vice versa. For such movements no separately movable parts are required according to my invention.

While I have shown and described several forms of the invention it will be understood that I do not wish to be limited thereto since various changes may be made therein without departing from the spirit of the invention.

What I claim is:

1. In a boiler cleaner, a rotary cleaner element, a steam valve, and a common means for opening the valve and rotating the cleaner element, such means operating to first open the valve, and then to rotate the cleaner in one direction, and upon reversal of said means to rotate the cleaner toward its original position with the valve still open, and during the end of the return movement of the cleaner to positively close the valve by mechanically forcing it against its seat.

2. In a boiler cleaner, a rotary cleaner element, a steam valve, and a common means for opening and closing the valve and rotating the cleaner, said means operating to first open the valve and then rotate the cleaner, and upon a reversal of said means move the cleaner toward its initial position with the valve still open, and means for positively closing the valve during the last part of the reverse movement of the cleaner, said last means acting to mechanically force the valve against its seat.

3. A boiler cleaner having a cleaner element and a valve provided with a stem, a common driving means therefor including a rotary sheave and a shaft, a connection between the sheave and shaft for rotating the latter, a pinion rotated by a gear on the shaft and carrying a fixed nut, a thread formed upon the valve stem and coacting with said nut to move the valve, a gear mounted upon the boiler cleaner, means for transmitting motion from said shaft to said gear, and a lost motion connection between said gear and said cleaner.

4. In a boiler cleaner, a rotary cleaner element, a steam valve for controlling passage of steam to said element, means connected with said steam valve for opening the latter and positively closing the same by forcing it mechanically against its seat, an operating device for said means, connections between said operating device and said valve opening and closing means causing the valve to open and close in accordance with the movements of said operating device, and a lost motion drive between said operating device and said cleaner element, permitting movement of the operating means to open said valve without turning the cleaner during the operation of said lost motion device, and means for supporting the reaction forces of said operating device independently of the cleaner, whereby there is no tendency to move the latter during the operation of said lost motion device.

5. In a boiler cleaner, a rotary cleaner element, a steam valve for controlling passage of steam to said element, means connected with said steam valve for opening the latter and positively closing the same by forcing it mechanically against its seat, an operating device for said means, connections between said operating device and said valve opening and closing means causing the valve to open and close in accordance with the movements of said operating device, and a lost motion drive between said operating device and said cleaner element, permitting movement of the operating means to open said valve without turning the cleaner during the operation of said lost motion device, means for supporting the reaction forces of said operating device independently of the cleaner, whereby there is no tendency to move the latter during the operation of said lost motion device, said connections between the operating device and the boiler cleaner comprising a pinion driven by the operating device, a loose gear coaxial with the cleaner, a stop connected to the cleaner, and a stop connected to said gear, said first-named stop being adapted to engage said last-named stop on each side when rotated in opposite directions.

6. In a boiler cleaner, a rotary cleaner element, a steam valve for controlling the passage of steam to said element, an operating

device, a threaded valve stem for said valve, a threaded member engaging the threads of said valve stem, means for producing relative motion between said last two members, said 5 means being driven by said operating device, a gear also driven by said operating device, a lost motion connection between said gear and said boiler cleaner constructed to permit an idle movement of said gear without rotating said cleaner, and a stop device on said cleaner for engaging said gear, whereby the gear 10 may rotate the cleaner.

In witness whereof, I have hereunto signed my name.
